VARIABLE PITCH IMPELLER

Cranmore W. Cline, United States Navy,
Jacksonville, Fla.

Application September 13, 1946, Serial No. 696,970

2 Claims. (Cl. 170—163)

(Granted under the act of March 3, 1883, as
amended April 30, 1928; 370 O. G. 757)

1

This invention relates to variable pitch impellers and more particularly to mechanisms for adjusting the pitch of the same.

An object of the invention is to provide an improved impeller of simple construction and adapted to have its pitch adjusted while in operation.

Other objects of the invention are to provide an improved variable pitch impeller for driving the reel of an aircraft tow target at different rates of speed; to provide an improved impeller, of the character described, having actuating means operable by the rotation of the impeller; to provide an improved mechanism for adjusting the pitch of an impeller during rotation of the same; to provide a control for the manual operation of the pitch of the blades on the impeller; to provide a control for utilizing, at the will of the operator, the impeller drive shaft as a source of power for the changing of the pitch of the impeller blades, in such a direction that will cause the impeller to stop rotating; to provide an improved impeller mechanism, of the character described, wherein the control means has connection with the impeller blades and with the drive shaft of said impeller and includes means for utilizing the rotation of said drive shaft to impart oscillation to said blades about their respective axes so as to vary the pitch of the same; and to provide improved elements and arrangements thereof in an impeller mechanism of the character described and for the purpose set forth.

In accomplishing these and other objects of the present invention, I have provided improved details of structure, the preferred form of which is illustrated in the accompanying drawings, wherein:

Fig. 1 is a transverse, vertical, sectional view of a portion of an aircraft fuselage having an impeller and control mechanism embodying the features of the present invention mounted thereon and therein and shown connected to a tow target reel.

Fig. 2 is a longitudinal, sectional view of the impeller.

Fig. 3 is a cross-sectional view, taken on the line 3—3 of Fig. 2.

Fig. 4 is an isometric view of a portion of the traversing mechanism, showing its relation to the drive shaft of the impeller.

Fig. 5 is a cross-sectional view, taken on the line 5—5 of Fig. 2, showing the connection between the impeller and the flexible cable which extends to the control mechanism.

2

Fig. 6 is a detailed sectional view of the control mechanism, taken on the line 6—6 of Fig. 1.

Fig. 7 is a cross-sectional view of the control mechanism, taken on the line 7—7 of Fig. 6.

Referring more in detail to the drawings: In Fig. 1, the numeral 10 designates a portion of the fuselage of an aircraft, such as an airplane, having an impeller 11 mounted thereon for driving a tow target reel 12, or other means, 10 which is mounted in a suitable frame 13. A driven shaft 14, coupling 15, and gear box 16 operatively connect the impeller 11 to the reel 12, the gear box permitting selective engagement and disengagement of said reel relative to the shaft and its coupling. As will be hereinafter more fully explained, the pitch of the impeller is adapted to be varied by a control mechanism 17 which is operatively connected to the gear box 16 by a flexible drive shaft or cable 18 and 20 to said impeller by a second flexible drive shaft or cable 19.

The impeller 11 includes an upright mounting support or standard 20 upon which a cylindrical nacelle or shell 21 (Fig. 2) is mounted in substantially parallel relation to the fuselage 10 (Fig. 1).

As shown in Fig. 2, a cylindrical bearing housing or collar 22 is disposed concentrically within the forward portion of the shell 21 and has an external, radial flange 23 adjacent its forward end, which flange overlies the forward open end of said shell and is secured thereto by suitable stud bolts 24 and nuts 25. The innermost end of the bearing housing 22 is of reduced diameter 35 and is provided with an internal, radial flange 26 to form an annular recess or socket 27 for receiving a ball bearing assembly 28. An axial drive shaft 29, having the bearing assembly 28 confined upon the inner end portion thereof, 40 extends through the bearing housing 22 and projects forwardly thereof. The rear extremity of the shaft 29 carries a bevelled pinion 30 which has its teeth in constant mesh with the teeth of a complementary pinion 31 mounted on the upper 45 end of the driven shaft 14, the latter extending into the shell 21 and being journaled therein by a ball bearing assembly 32.

A hub 33, having an axial bore 34, is keyed or otherwise secured upon the forward portion of 50 the drive shaft 29 and is confined thereupon by a suitable nut 35. The hub 33 is preferably hexagonal in cross-section and has a plurality of radial sockets 36 (Fig. 3) which are preferably equally-spaced and have been illustrated as being 55 four in number. Each socket 36 is adapted to

receive the shank or root of a blade 37 and is progressively enlarged or stepped outwardly to provide a plurality of counterbored or shouldered portions. Each blade 37 has its shank formed complementary to its socket and carries in sequential order a small ball bearing assembly 38, a spur gear 39, Fig. 2, a lock nut 40 and a large ball bearing assembly 41 which engage within the counterbored portions of said socket. A housing or casing 42 encloses the hub and includes a nose or cap section 43 and coacting annular cages or sections 44 and 45, the latter encircling said hub and rotatably confining the blades shanks within their sockets.

As shown in Figs. 2 and 3, the hub 33 is formed with a plurality of longitudinal ports or keyways 46 intermediate and extending at right angles to the sockets 36, with each keyhole communicating with the adjacent counterclockwise socket. A reciprocable bar or rod 47, having a gear rack 48 secured thereto, is slidably mounted in each keyhole 46 and projects rearwardly therethrough. The teeth of each gear rack 48 are in constant mesh with the teeth of the adjacent counterclockwise spur gear 39, whereby the blade upon which said gear is mounted is oscillated about its axis by reciprocation of the rod 47 carrying said rack. In effect, the rods and gear racks form a part of the control mechanism 17 and are adapted to be simultaneously and uniformly reciprocated by means of an actuating or connecting member 49 which is slidably confined upon the drive shaft 29 rearwardly of the hub.

As is most clearly shown in Fig. 4, the member 49 includes a radial flange 50 and a plurality of equally-spaced, rearwardly-directed fingers 51 which are arcuate in cross-section and snugly engage the peripheral surface of the shaft 29 (Fig. 2). Keyholes 52 are formed in the flange 50 of the connecting member for receiving the rearward ends of the rods 47 and connecting the same to said member. The fingers 51 extend longitudinally between radial ribs or lugs 53 formed on the shaft 29 and have their rearward or free ends reduced in thickness for receiving an annular, splined spacer 54 and a pair of annular nuts or rings 55 which are screw-threaded upon said fingers ends and confine the spacer thereupon with its splines between said fingers. Due to the relation of the fingers and the lugs 53, the member 49 rotates with the drive shaft and is slidably longitudinally thereof. For receiving an annular, rearwardly-directed bearing collar 56 formed on the hub 33 (Fig. 2), the inner, forward portions of the fingers are recessed as shown by the numeral 57 (Fig. 4).

A ball bearing assembly 58 is mounted within the bearing housing 22, Fig. 2, forwardly of its flange 23 and in surrounding relation to the fingers 51, for centering the connecting member 49 within said housing and permitting relative rotation and reciprocation of said member. In order to reciprocate the connecting member, a pair of annular, traversing elements or guides 59 and 60 are disposed within the rearward portion of the bearing housing 22 concentrically of the drive shaft 29. The outer or female guide 59 is fixed against rotation within the bearing housing by suitable means, such as splines or keys 61, and is internally recessed to receive a ball bearing assembly 62 which is confined upon the rearward ends of the fingers 51 of the connecting member by the nuts 55. An annular bearing cap 63 connects the female guide to the bearing assembly 62, whereby reciprocation of said guide is trans-

mitted to the member 49 without interfering with the rotation of said member. Forward reciprocation of the member is limited by a spacer ring 64 which encircles the fingers of the connecting member forwardly of the bearing assembly 62 and which is adapted to engage the bearing assembly 58 upon such reciprocation.

The inner or male guide 60 is screw-threaded within the outer, non-rotatable guide 59 and is 10 rotatably supported by an annular bearing member 65 which is secured to the bearing housing 22 immediately forward of its recess 27. An internal, annular flange portion 66 projects rearwardly from the guide 60 and is rotatably confined upon the bearing member 65 by a coacting radial flange or shoulder 67 formed internally of and at the forward end of said bearing member. For imparting rotation to the inner guide 60 so as to reciprocate the outer guide 59, the flange portion 66 of said inner guide has a worm gear 68 secured externally thereon. A suitable thrust bearing 69 encircles the flange portion and bearing member rearwardly of the worm gear 68.

As is clearly shown in Fig. 5, a worm 70 has its teeth in constant mesh with the teeth of the worm gear 68. The worm 70 is carried by a short shaft 71 which is journaled in the bearing housing 22 and extends through the wall of the shell 21 into the standard 20 (Fig. 2), being suitably 25 coupled to the flexible shaft 19. By virtue of the foregoing arrangement, rotation of the flexible shaft 19 is transmitted through shaft 71, worm 70 and worm gear 68 to the inner traversing guide 60. Since the outer traversing guide 59 is keyed 30 against rotation, rotation of the inner member causes sliding movement of said outer member. This movement is imparted through the bearing assembly 62, actuating member 49, and rods 47 to the gear racks 48 so as to oscillate the spur gears 39 and the blades 37 about their respective axes during rotation of the hub 33 and said blades about the longitudinal axis of the shaft 29.

Rotation of the flexible shaft 19 is affected by means of the control mechanism 17. As shown 45 in Figs. 1, 6 and 7, the mechanism includes a rectangular housing or casing 72 mounted on the frame 13 and having a pair of parallel shafts 73 and 74 journaled therein. The flexible shafts 18 and 19 are connected to the shafts 73 and 74, 50 respectively, which shafts have drums or rollers 75 and 76 mounted thereon, whereby said shaft 73 and its roller 75 are constantly driven by said flexible shaft 18. An idler assembly 77 is disposed within the casing 72 for operatively connecting the rollers 75 and 76 and includes a spring-pressed yoke member 78 having its parallel legs or arms extending at right angles to said rollers between the shafts 73 and 74. The yoke member 78 rotatably supports an idler drum or roller 79, by means of a suitable shaft 80, which roller is parallel to and adapted to be engaged with the rollers 75 and 76 upon movement of said yoke member in a plane transverse to the longitudinal axes of said latter rollers.

65 A cam element 81 is pivotally supported externally of the casing 72, between suitable lugs or ears 82, in engagement with a pin or button 83 carried by the yoke member and extending through an opening in said casing, whereby pivoting of the cam element in a counter-clockwise direction causes inward reciprocation of said yoke member and engagement of its idler roller with the rollers 75 and 76. The button 83 is held in engagement with the cam element 81 by a coiled spring 84 which is confined between

an annular boss 85 formed internally of the casing and a co-axial pin 86 carried by the yoke member opposite said button. Displacement of the yoke member is prevented by the engagement of the button in the casing opening and the co-action of the pin 86 with the annular boss 85. A U-shaped guide element or bracket 87 is mounted internally of the casing in engagement with the yoke member for preventing turning or pivoting of said member about the axes of its button and pin. Upon engagement of the rollers, rotation is imparted to the roller 76, shaft 74, flexible shaft 19, shaft 71, Fig. 5, and worm 70 so as to drive the worm gear 68 and thereby turn the blades 37 about their respective axes, as explained hereinbefore. It is pointed out that one end of the shaft 74 extends entirely through the casing and has a hand wheel 88, Fig. 6, mounted on its projecting end to permit manual oscillation of the blades and adjusting of the pitch thereof.

Operation

The operation of a variable pitch impeller and control mechanism therefor, constructed as described, is as follows:

During take-offs and landings, the blades 37 of the impeller are full feathered to offer as little wind resistance as possible. The feathering of the blades is accomplished manually, by means of the hand wheel 88 upon take-offs and either manually or mechanically by pivoting the cam element 81, upon landings.

When it is desired to rewind the tow target reel 12, the driven shaft 14 is operatively connected to said reel by manipulation of the gear box 16. Since the shaft 14 is driven by its connection with the drive shaft 29, rotation of the impeller blades and their hub 33 is transmitted to the reel. Although rapid rewind is desirable, it is essential to control the speed of rotation of the impeller to prevent overspeeding of the same. The load imposed on the impeller is constantly reduced by reeling in of the cable with the result that the speed of said impeller is increased. By increasing the pitch of the impeller blades, the rotational speed of the same is decreased and the rate of rewind reduced. This control is important during completion of the rewind and permits "inching" in of a target sleeve (not shown).

In order to feather or decrease the pitch of the impeller blades, the cam element 81 is swung in a counter-clockwise direction so as to move the idler assembly 77 inwardly or to the right (Figs. 6 and 7) and move its roller 79 into engagement with the rollers 75 and 76. Since the roller 75 is rotated by the connection of its shaft 73 to the flexible shaft 18, in turn driven by its connection with the gear box 16, the roller 76 and its shaft 74 are rotated by the aforesaid engagement of the rollers. This rotation is imparted to the inner traversing member 60 through the flexible shaft 19, shaft 71, worm 70 and worm gear 68 (Figs. 2 and 5).

Due to the provision of the keys 61 and the screw-threaded connection between the traversing guides, the outer traversing guide 59 is slid outwardly longitudinally of the shaft 29 by rotation of the guide 60. The bearing assembly 62 and cap 63 impart similar longitudinal movement to the actuating member 49 so as to reciprocate the rods 47 and their gear racks 48 forwardly, thereby turning the spur gears 39 and the blades 37, upon which said gears are mounted, about their respective axes. In this manner, the

pitch of the blades is increased so as to decrease the rotational speed of the same and thereby reduce the rate of rewind of the reel 12.

Full feathering of the blades is accomplished by continued actuation of the control mechanism 17 which moves the racks 48, rods 47, member 49, bearing assembly 62, cap 63 and guide 59 outwardly until the spacer ring 64 engages the bearing assembly 58. It is pointed out that actuation of the control mechanism continues so long as the cam element 81 maintains the idler assembly 77 inwardly of the casing 72 with its roller 79 in engagement with the rollers 75 and 76. Upon release of the cam element, the compression of the spring 84 urges the assembly outwardly or to the left (Figs. 6 and 7) so as to disengage the rollers and thereby render the control mechanism inoperative. Due to the construction of the impeller, the blades thereof will retain the pitch to which the same have been adjusted at the moment of disengagement of the rollers and non-operation of the control mechanism.

As has been explained, the pitch of the impeller blades may be varied manually, at will, by the provision of the direct connected shaft 19 between the operator and the pitch changing mechanism, manually controlled by the hand wheel 88. Of the three rubber covered rollers in the control box, two of these rollers are respectively connected to the flexible shafts. One of the drive shafts goes to the pitch changing device and the other one goes to the impeller main power drive shaft. The third and last rubber covered roller is merely an idler and is there to provide a means of coupling, at will, the two other before mentioned rollers. When the two rollers that are connected to the flexible drive shafts are coupled together, by means of the idler roller, the following result is obtained. The roller that is driven by the impeller main drive shaft turns the idler roller, and this idler roller in turn, turns the roller on the pitch control drive shaft in a direction which tends to stop the rotation of the impeller. This result may be accomplished with or without a load on the impeller main drive shaft. If there is no load on the drive shaft then the impeller completely feathers itself and stops. If there is a load on the main drive shaft then the pitch setting of the blades will be one that balances, without causing rotation. When the rollers are disengaged, the roller 76, its shaft 74 and the flexible shaft 19 may be readily rotated by hand to actuate the traversing guides and their associated elements.

While I have shown but one embodiment of my invention, it is susceptible to modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A variable pitch impeller for driving the reel of a tow target including, a rotatable shaft, a hub mounted on the shaft and having a plurality of radial sockets, a blade having its root rotatably mounted in each socket, a spur gear carried by the root of each blade, gear racks reciprocably mounted in the hub in meshing engagement with the spur gear for adjusting the pitch of the blades, a member slidably mounted on said shaft

and fixed against rotation relative thereto, the member having connection with the gear racks for reciprocating the same, a worm gear rotatably mounted on said shaft and having screw-threaded connection with said member, a worm drive for imparting rotation to the worm gear so as to slide said member and actuate said gear racks, a control mechanism having a pair of spaced rotatable rollers, a flexible shaft operatively connecting one of the rollers to said impeller shaft, the other roller being operatively connected to the worm drive, means connected to said latter roller permitting manual rotation of the same so as to effect adjustment of the blade pitch, an idler roller adapted to be moved into engagement with said rollers whereby the rotation of said impeller shaft is transmitted to said worm drive, spring-pressed means supporting the idler roller out of engagement with said rollers, and cam means engageable with the spring-pressed means for moving said idler roller into engagement with said rollers.

2. A variable pitch impeller including, a rotatable shaft, a hub mounted on the shaft and having a plurality of radial sockets, a blade having its root rotatably mounted in each socket, gear teeth carried by the root of each blade, gear racks reciprocably mounted in the hub in meshing engagement with the gear teeth for adjusting the pitch of the blades, a member slidably mounted on said shaft and fixed against rotation, the mem-

10
